STRIPPING MECHANISM FOR CONVEYERS.
APPLICATION FILED NOV. 22, 1911.

Patented Sept. 23, 1913.

2 SHEETS—SHEET 2.

UNITED STATES PATENT OFFICE.

JAMES E. KELSO, OF ROCHESTER, NEW YORK, ASSIGNOR TO AMERICAN LAUNDRY MACHINERY COMPANY, OF CINCINNATI, OHIO, A CORPORATION OF OHIO.

STRIPPING MECHANISM FOR CONVEYERS.

1,073,907.

Specification of Letters Patent. Patented Sept. 23, 1913.

Application filed November 22, 1911. Serial No. 661,793.

To all whom it may concern:

Be it known that I, JAMES E. KELSO, of Rochester, in the county of Monroe and State of New York, have invented certain new and useful Improvements in Stripping Mechanism for Conveyers; and I do hereby declare the following to be a full, clear, and exact description of the same, reference being had to the accompanying drawing, forming a part of this specification, and to the reference-numerals marked thereon.

The present invention relates to improvements in stripping mechanisms for conveyers of the type embodying, generally, an endless conveyer provided with goods holders, such as are employed in laundry dry rooms, a stripper adapted to coöperate with the conveyer to strip the goods from the holders, and it has for its object to afford means for loosening the goods on the holders prior to the stripping operation.

A further object of my invention is to provide a movable stripping device, upon which is mounted a member adapted to engage the goods on the holders prior to the stripping operation, and to lift, or loosen the goods so that they will be readily pushed off by the stripper.

To these and other ends the invention consists in certain improvements and combinations of parts all as will be hereinafter more fully described, the novel features being pointed out in the claims at the end of the specification.

In the drawings: Figure 1 is a view in side elevation of a portion of a laundry dry room conveyer embodying a preferred arrangement of parts in accordance with the present invention, a series of collars being illustrated on the goods holders, and the loosening member being shown in dotted and full lines, respectively, to indicate its operation on the collar; Fig. 2 is a detail view in side elevation showing a single goods holder, the stripping device being in normal position, and Fig. 3 is a vertical sectional view, the stripping mechanism appearing in elevation.

Similar reference numerals throughout the several figures indicate the same parts.

In the operation of dry room conveyers of the type mentioned, the collars, being first washed and starched, are arranged on the conveyer, each goods holder containing a

collar, and in this manner they pass through the dry room. The goods holders are more or less V-shaped, as shown in the drawings, in order to retain the collars readily, and as the collars dry, they adhere closely to the holders, and become more or less fastened at the bottom of the V-shaped holders, owing to the hardening of the starch, with the result that when the stripping mechanism is reached and the stripper engages a goods holder, more or less resistance is offered by the collar, and the buttonhole is strained and in many instances torn by the stripper, as the collar is forced from its position at the bottom of the holder. This I overcome by making provision for loosening the collars on the holders before they are engaged by the stripper.

The embodiment herein illustrated is applied to a conveyer traveling on a track 1 and including a series of links 2, each of which forms a part of an upright 3, provided with rollers 4 at its upper end, goods holders 5 at its lower end, and an enlargement 6 between the upper and lower ends for a purpose that will appear hereinafter. Secured to the track 1 is a suitable fixed support on which the stripping device is mounted, and comprising in the present instance the frame 7 carrying guides 8 which serve to center the goods holders as they move into coöperative relation with the stripping device.

The stripping device preferably embodies a body portion 9 which is slightly concaved along its upper edge as indicated at 10, and is provided with suitable slots or recesses 11 at its ends to embrace the goods holders during the movement of the latter relatively to the stripping device. The stripping device is further provided with suitable ears 12, by which it is pivotally mounted on the arms 13 of the frame 7, and with upstanding portions 14 arranged to be engaged by the enlargements 6 previously referred to, the stripping device being actuated by the movement of the conveyer as each enlargement 6 comes in contact with the upstanding portions 14.

In order to enable the collars to be stripped readily from the holders, and to obviate any possibility of their being strained or torn, it is desirable to engage the collars and loosen them on their holders, prior to

the engagement of the stripping device. This may be accomplished in different ways, and the present embodiment illustrates a convenient form of goods loosening member comprising a downwardly projecting extension 15 on the stripping device, bent forwardly at its lower end, and carrying at its extremity a suitable rod, or bar, held in place by a set screw 16, and constituting laterally extending arms 17, which are preferably provided with forwardly extending portions 18 at their outer ends. By forming the arms with the forwardly extending portions their proper engagement with the collars is assured obviating any possibility of the collars passing without being engaged thereby.

The operation of the device will be apparent from an inspection of Fig. 1. While 20 one pair of goods holders is being engaged by the stripping device to remove the collars, the collars on the next adjacent pair of holders are engaged by the loosening member and moved to approximately the 25 position shown. The loosening member strikes the collars at points near their lower ends, as shown in dotted lines, the initial point of engagement being in a plane considerably lower than that of the stripping 30 device. This causes the collar to be lifted, and loosened on its holder, in a manner that prevents tearing, such as occurs when the collar is engaged near its point of support. In the actual operation of the parts, the 35 collars on the two pairs of holders next adjacent to the stripping device are affected by the loosening member, as shown, although it is only essential that the collars next adjacent to the stripping device be loosened prior 40 to their being engaged by the stripping device.

While I have disclosed in this application a particular embodiment of my invention, it is not limited to the precise structure set 45 forth, and is applicable to various forms of conveyers without departing from the essential elements of the invention which consist in providing means for engaging a piece of goods at a point somewhat removed from 50 its point of support, in order to loosen the goods on the holder prior to its removal.

I claim as my invention:

1. In a stripping mechanism for conveyers, the combination with a conveyer and a 55 goods holder carried thereby, of a movable stripping device mounted on a fixed support and coöperating with said holder to remove the goods therefrom, means carried by the conveyer for actuating the stripping 60 device, and a goods loosening member arranged to engage the goods on the holder prior to the engagement of the stripping device therewith.

2. In a stripping mechanism for conveyers, the combination with a conveyer and a 65

goods holder carried thereby, of a movable stripping device mounted on a fixed support and coöperating with said holder to remove the goods therefrom, means carried by the conveyer for actuating the stripping device, 70 and a movable goods loosening member arranged to engage the goods on the holder prior to the engagement of the stripping device therewith.

3. In a stripping mechanism for conveyers, the combination with a conveyer and a 75 goods holder carried thereby, of a movable stripping device mounted on a fixed support and coöperating with said holder to remove the goods therefrom, means carried by the 80 conveyer for actuating the stripping device, and a goods loosening member mounted on the stripping device and arranged to engage the goods on the holder prior to the engagement of the stripping device therewith. 85

4. In a stripping mechanism for conveyers, the combination with a conveyer and a goods holder carried thereby, of a stripping device coöperating with said holder to remove the goods therefrom, and a goods 90 loosening member arranged to engage the goods on the holder prior to the engagement of the stripping device therewith.

5. In a stripping mechanism for conveyers, the combination with a conveyer and a 95 goods holder carried thereby, of a movable stripping device mounted on a fixed support and coöperating with said holder to remove the goods therefrom, means carried by the conveyer for actuating the stripping device, 100 and a member carried by the stripping device arranged to engage the goods in a horizontal plane below the stripping device and prior to the engagement of the stripping device therewith. 105

6. In a stripping mechanism for conveyers, the combination with a conveyer and a goods holder carried thereby, of a movable stripping device mounted on a fixed support and coöperating with said holder to remove 110 the goods therefrom, means carried by the conveyer for actuating the stripping device, and a goods loosening member comprising a downwardly projecting extension on the stripping device and a laterally extending 115 arm at the lower end of said extension.

7. In a stripping mechanism for conveyers, the combination with a conveyer and a pair of goods holders carried thereby, of a movable stripping device mounted on a fixed 120 support and coöperating with said holders to remove the goods therefrom, said stripping device embodying a body portion having slots or recesses to embrace the holders, and means carried by the conveyer for actuating the stripping device. 125

8. In a stripping mechanism for conveyers, the combination with a conveyer and a goods holder carried thereby, of a stripping device coöperating with said holder to re- 130

move the goods therefrom, means for actuating the stripping device and a goods loosening member arranged to engage the goods on the holder prior to the engagement of the stripping device therewith.

9. In combination with a conveyer and a goods holder carried thereby, a goods loos-

ening member arranged to engage the goods on the holder in advance of its point of removal from the holder.
